UNITED STATES PATENT OFFICE.

CHARLES A. FABER, OF TOLEDO, OHIO.

FOUNTAIN-PEN.

SPECIFICATION forming part of Letters Patent No. 778,407, dated December 27, 1904.

Application filed November 16, 1903. Serial No. 181,392.

To all whom it may concern:

Be it known that I, CHARLES A. FABER, a citizen of the United States, residing at Toledo, in the county of Lucas and State of Ohio, have 5 invented certain new and useful Improvements in Fountain-Pens; and I do declare the following to be a full, clear, and exact description of the invention, such as will enable others skilled in the art to which it appertains to make and 10 use the same.

My invention relates to improvements in fountain-pens of the self-filling type.

The object of my invention is to provide a device of this character which will be simple 15 in construction, durable in use, efficient in operation, and comparatively inexpensive to manufacture.

With this and other objects in view the invention consists of certain novel features of 20 construction, combination, and arrangement of parts, as will be more fully described, and particularly pointed out in the appended claims.

In the accompanying drawings, Figure 1 is 25 an elevation of a fountain-pen constructed in accordance with my invention. Fig. 2 is a longitudinal section through the same. Fig. 3 is a similar view illustrating the manner of using the filling device. Fig. 4 is a transverse section taken on the line $\alpha\alpha$ of Fig. 2. Fig. 5 is a perspective view of the compressor-bar and its attached parts removed from the penholders.

In the embodiment of my invention as illustrated in the drawings the numeral 1 denotes the hollow cylindrical body of a penholder having one of its ends closed and its other end provided with a removable pen-section 2, carrying at its outer end a pen 3, which when 35 not in use is inclosed and guarded by the usual removable cover or cap 4. To the inner end of the pen-section 2 is secured at 5 the open end of a collapsible ink-container 6, which is preferably in the form of a sack or bag of 40 rubber or other suitable material. Said sack or container is of such a nature or construction that it will immediately expand or return to its normal position after it has been collapsed, and it is disposed within the body of 45 the penholder with its open end communicat-

ing with the usual ink passage or duct 7 in the pen-section 2 to permit the ink to feed from said container to the points of the pen 3.

The penholder is filled by placing its point 3 in ink, compressing or collapsing the container or sack 6, and then allowing it to expand and draw in the ink. In order to collapse the sack 6, a compressor-bar 8 is disposed longitudinally within the penholder and engages the sack. Said compressor-bar is 55 preferably stamped from a piece of sheet metal, and at the center of its sides two lugs 9 are bent up at right angles, so as to project into a slot or opening 10 in the body of the holder. Between the outer ends of these lugs 60 a lever 11 is pivoted upon a pin 12. Said lever is pivoted adjacent to one of its ends, and its longer end or arm 13 is adapted when in 65 its normal position to lie flush with the outer surface of the body 1 in a recess 14 adjacent 70 to the slot 10. The short end or arm of the lever 11 is square and adapted to coact with a locking-spring 15, riveted or otherwise secured to the top of the compressor-bar, as 75 clearly seen in Fig. 5. The outer end of said 75 spring is bent or hook-shaped, as shown at 16, to engage a shoulder 17 in the pen-body, formed adjacent to the opening or slot 10. When the lever 11 is in its lowered position at right angles to the lugs 9, its square end 80 engages the spring locking-arm 15 and holds its end 16 in engagement with the shoulder 17, thereby locking the lever in its lowered position and preventing any movement of the 85 compressor-bar. When the lever is swung up 85 to its vertical position, as shown in Fig. 3, the spring 15 is released, and its end disengages from the shoulder 17 to permit the lugs 9 and lever 11 to be reciprocated in the slot 10. When the lever is forced inwardly, the 90 compressor-bar 8 will collapse the sack or container 6, which will expand as soon as released.

The operation of my invention will be readily understood. The lever is swung to its 95 elevated position, forced inwardly to collapse the ink-sack, then withdrawn and swung down to its lower position, the point of the pen being submerged in ink to permit the same to be drawn into the sack as it expands.

It will be seen that I have provided a simple, durable, and efficient filling device for fountain-pens, which may be manufactured at small cost. As the device is inclosed within 5 the pen-body with its lever lying flush with the outer surface of the body, the holder has a perfectly smooth outer surface and resembles the ordinary fountain-pens.

From the foregoing description, taken in 10 connection with the accompanying drawings, the construction and operation of the invention will be readily understood without requiring a more extended explanation.

Various changes in the form, proportion, 15 and the minor details of construction may be resorted to without departing from the principle or sacrificing any of the advantages of this invention.

Having thus described my invention, what 20 I claim as new, and desire to secure by Letters Patent, is—

- 25 1. A fountain-pen comprising a suitable holder having an opening or slot, a collapsible ink-container in said holder, a compressor-bar in said holder coacting with said collapsible container, and an operating device carried by and pivotally connected to said compressor-bar and projecting through the opening in said holder, substantially as described.
- 30 2. A fountain-pen comprising a suitable holder having an opening or slot, a collapsible ink-container in said holder, a compressor-bar in said holder coacting with said collapsible container, a lever carried by and having a pivotal connection with said compressor-bar and adapted to be reciprocated in the slot in said holder to actuate said compressor-bar, and means for locking said lever and compressor-bar, substantially as described.
- 35 3. A fountain-pen comprising a suitable holder having an opening or slot, a collapsible ink-container in said holder, a compressor-bar in said holder coacting with said collapsible container, a lever carried by and having a pivotal connection with said compressor-bar and adapted to be reciprocated in the slot in said holder to actuate said compressor-bar, and a spring device actuated by said lever for hold-

ing the same and the compressor-bar against movement, substantially as described. 50

4. A fountain-pen comprising a holder having a slot or opening and a recess adjacent to said opening, a collapsible ink-container in said holder, a compressor-bar in said holder adapted to collapse said container and having a lug or arm projecting into the opening in said holder, a lever pivoted intermediate its ends to said lug and adapted to lie in the recess in said holder, and a spring engaging one end of said lever to hold it in said recess, substantially as described. 55

5. A fountain-pen comprising a holder, having a slot or opening and a recess adjacent to said opening, a collapsible ink-container in said holder, a compressor-bar in said holder 60 adapted to collapse said container and having a lug or arm projecting into the opening in said holder, a lever pivoted intermediate its ends to said lug and adapted to lie in the recess in said holder, and a locking-spring having 65 a bent end adapted to be forced by said lever into engagement with the holder to lock the compressor-bar against movement and the lever in the recess in said holder, substantially as described. 70

75 6. A self-filling fountain-pen comprising a hollow holder having an opening or slot, a recess and a shoulder adjacent to said slot, a collapsible ink-sack in said holder, a compressor-bar in said holder adapted to collapse said sack 80 and having lugs projecting into the opening in said holder, a lever pivoted intermediate its ends to said lugs and adapted to lie in the recess in said holder, a spring secured to said compressor-bar having a bent end adapted to 85 be held in engagement with the shoulder of said holder by one end of said lever, substantially as described.

In testimony whereof I have hereunto set my hand in presence of two subscribing witnesses. 90

CHARLES A. FABER.
